UNITED STATES PATENT OFFICE.

EVERETT L. SARGENT, OF PATTEN, MAINE.

CANOE ATTACHMENT.

1,041,679.

Specification of Letters Patent.

Patented Oct. 15, 1912.

Application filed February 28, 1912. Serial No. 680,400.

To all whom it may concern:

Be it known that I, EVERETT L. SARGENT, a citizen of the United States, residing at Patten, in the county of Penobscot and 50 State of Maine, have invented new and useful Improvements in Canoe Attachments, of which the following is a specification.

The invention relates to canoes, and more particularly to the class of buoyant attach- 10 ments for canoes.

The primary object of the invention is the provision of an attachment of this character in which a canoe, when overturned, will be prevented from sinking, as the same will be 15 rendered buoyant, thereby assuring safety, when it is being used.

Another object of the invention is the provision of an attachment of this character which is simple in construction, reliable and 20 efficient in its purpose, and inexpensive in manufacture.

With these and other objects in view, the invention consists in the construction, combination and arrangement of parts, as will 25 be hereinafter more fully described, illustrated in the accompanying drawings, and pointed out in the claim hereunto appended.

In the drawings: Figure 1 is a perspective view of a canoe, showing the attachment 30 constructed in accordance with the invention mounted thereon. Fig. 2 is a top plan view.

Fig. 3 is a sectional view on the line 3—3 of Fig. 2, looking in the direction of the arrow. Fig. 4 is a perspective view of the 35 attachment removed. Fig. 5 is a perspective view of an air bag removed from its covering.

Similar reference characters indicate corresponding parts throughout the several 40 views of the drawings.

Referring to the drawings by numerals, 5 designates the body of a canoe, which is of the ordinary well-known construction, and in the bow and stern thereof is adapted 45 to be mounted the buoyant attachment, pres- ently described.

Each buoyant attachment comprises an inflatable air bag 6 which may be of any desirable shape, that is to say, of a shape to fit snugly within either the bow or stern of the body 5 of the canoe, it being understood, of course, that two of the air bags are used in the canoe, but for the sake of brevity, only one bag and its covering will be herein described. 55

The bag 6 is formed at one end with an air inlet tube 7, to which may be attached any suitable pumping apparatus for inflating the bag with air. The bag 6 is insertible within an outer covering 8 which is preferably constructed from either canvas or leather, and of complementary shape thereto, one end of the covering being formed with an opening 9, through which is inserted the bag 6, and this opening is adapted to be closed by 60 means of a lacing 10, as shown.

Provided at the open end of the covering 8 is a band 11, provided at intervals with eyelets 12 for receiving any suitable fastening medium, whereby the said covering may 65 be secured to the body 5 of the canoe at the desired point of location therefor.

From the foregoing, taken in connection with the accompanying drawings, it is thought that the construction and purpose of 70 the invention will be readily understood, without requiring a more extended explanation.

What is claimed is:

The combination with a canoe, of inflata- 80 ble air bags, a covering for receiving each of said air bags and having an opening in one end, means for closing said open end of the covering, and means on the coverings for the securing thereof in the bow and stern of 85 the canoe.

In testimony whereof I affix my signature in presence of two witnesses.

EVERETT L. SARGENT.
